(57) **CLAIM**

The ornamental design for a pedal base with foot inserts for a scooter, as shown and described.

DESCRIPTION

FIG. 1 is a front perspective view of a pedal base with foot inserts for a scooter according to my new design;

FIG. 2 is a left side view thereof;

FIG. 3 is a right side view thereof;

FIG. 4 is a top view thereof;

FIG. 5 is a bottom view thereof;

FIG. 6 is a rear view thereof;

FIG. 7 is a front view thereof; and,

FIG. 8 is a rear perspective view thereof.

The broken lines represent environmental structure or unclaimed portions of the pedal base with foot inserts for a scooter and do not form a portion of the claimed design. The foot inserts are shown in stippling to indicate a contrasting material or color.
